DESIGN FOR A COMBINED NAIL FILE AND PIPE TAMP

Harry C. French, Cleveland, Ohio

Application June 15, 1937, Serial No. 69,855

Term of patent 7 years

To all whom it may concern:

Be it known that I, Harry C. French, a citizen of the United States, residing at Cleveland, in the county of Cuyahoga and State of Ohio, have invented a new, original, and ornamental Design for a Combined Nail File and Pipe Tamp, of which the following is a specification, reference being had to the accompanying drawing, forming part thereof, and wherein Fig. 1 is a front elevation, Fig. 2 a side elevation, Fig. 3 a rear elevation, and Fig. 4 a plan view of a combined nail file and pipe tamp, showing my new design, and Figs. 5 and 6 are sections of the respective lines 5—5 and 6—6 of Fig. 3.

I claim:

The ornamental design for a combined nail file and pipe tamp as shown.

HARRY C. FRENCH.
